UNITED STATES PATENT OFFICE.

FREDERICK A. GERCICH AND JOSEPH B. GARDNER, OF OAKLAND, CALIFORNIA, ASSIGNORS TO HAMMER-BRAY COMPANY, OF OAKLAND, CALIFORNIA, A CORPORATION OF CALIFORNIA.

OVEN DOOR.

Application filed November 30, 1924. Serial No. 751,011.

Our invention relates to oven doors and particularly to counter-balancing means for oven doors arranged to swing about a horizontal axis at their lower edge.

6 An object of the invention is to provide an oven door with counter-balancing means which utilizes a torsion spring without necessitating the external indication of the presence of such spring.

10 Another object of the invention is to provide a counter-balancing device of the class described which will allow the independent removal of a door from its frame.

15 Our invention possesses other objects and features of advantage, some of which, with the foregoing, will be set forth in the following description of the preferred form of our invention which is illustrated in the drawings accompanying and forming part of 20 the specification. It is to be understood that we do not limit ourselves to the showing made by the said drawings and description, as we may adopt variations of the preferred form within the scope of our invention as set forth in the claims.

25 Referring to said drawings:

Figure 1 is a fragmentary inside sectional view of an oven equipped with the preferred embodiment of the device of our invention, 30 the oven door being in closed position.

Figure 2 is a view similar to that of Figure 1, showing the oven door in open position.

Figure 3 is a sectional view taken on the line 3-3 in Figure 1.

Figure 4 is a view similar to that of Figure 2, showing another embodiment of our invention.

Heretofore, in oven doors equipped with 40 counterbalancing springs of the torsion type, the springs have been arranged in coaxial relation with the pivotal axis of the doors, and the structure involved has therefore necessitated the protrusion of one or more 45 parts of the stove adjacent the spring. But present practice in stove design has decreed that stove fronts shall be smooth and unbroken, with the result that previously used constructions involving the use of counter- 50 balancing springs of the torsion type have become obsolete and other more complicated means of counterbalancing have been resorted to. In accordance with our invention,

however, a structure is provided by which a torsion spring may be simply and satisfactorily applied for counterbalancing oven doors of the usual type without presenting any external evidence of the presence or use of a spring. Briefly expressed, the means of our invention comprises a torsion spring 55 mounted behind the door frame and arranged to be actuated by a trunnion extending rearwardly from the door, the trunnion also preferably serving to provide a pivotal bearing for the door and a stop to hold the 60 door in perpendicular relation to the stove front when the door is in open position. In this manner, the counterbalancing structure is entirely situated behind the plane of the 65 stove front and therefore does not affect the 70 external design of the stove.

As here shown, the device of our invention is applied to the door 6 of an oven having a side wall 7 and a door frame 8. The door frame is here shown provided with perforations 9 adjacent the bottom of the door opening therein and arranged to receive trunnions 12 extending rearwardly from the lower edge of the door. The portion of the door adjacent the lower edge 13 of each 80 perforation 9 is preferably formed with inwardly extending lugs 15 which cooperate with the edge 13 to provide a bearing of circular section which seats in a cooperating semicylindrical bearing recess 14 provided in 85 the lower forward portion of the trunnion. In this manner, the pivotal axis of the door is defined as the axis of the bearing recess 14, and the bearing so provided prevents outward as well as downward displacement of 90 the door during its pivotal movement.

Counterbalancing of the weight of the door as it is lowered to its open position is here shown provided for by means of a torsion spring 16 formed spirally and loosely 95 mounted in part on a cam shaft 17. As here shown, the shaft 17 extends from and is pivotally mounted in a bearing 18 provided in a plate 19 which is preferably secured to the side wall 7 by means of bolts 100 20. To provide a shaft bearing of necessary length, the bearing 18 preferably extends about half way of the length of the shaft 17, a portion 21 of the latter being reduced to fit in the bearing, so that the outer surface 105 of the bearing may lie within the portion

of the spring not carried on the shaft. The end 22 of the spring adjacent the plate 19 is preferably extended tangentially from the springs and when the device is operatively assembled, is arranged to rest below and against a projection 23 extending transversely from the plate. The other end 24 of the spring is bent radially inward and is arranged to be fixed to the shaft by insertion in a radially extending socket 25 provided therein.

As here shown, the shaft 17 is arranged to be held in the bearing 18 by means of a 15 studbolt 26 and washer 27, the bolt head and washer being disposed in a countersunk portion 28 of the bearing. In this manner, when the plate is secured to the wall 7, the studbolt 26 is prevented from becoming entirely disengaged from the shaft even though 20 it may become loosened.

Operative connection between the spring and door is here shown provided by means of a cam connection between them. Fixed to the outer end of the shaft 17 is a cam 29 which is arranged to cooperate with the trunnion 12 in applying the torsional strength of the spring 16 as a means for counterbalancing the door during its movement and when it is in lowered position. As here shown, the trunnion 12 is provided with a transverse notch 30 mediate of its outer edge and in which the end 31 of the cam is arranged to seat when the door is in raised position. The portion 32 of the trunnion edge portion below the notch 30 is preferably smoothly curved so that as the trunnion is pivotally moved upward upon downward movement of the door, the cam end 31 will be simultaneously rotated upwardly and 40 slidably engage the surface of the trunnion portion 32, it being noted that when the door is in fully extended position, as shown in Figure 2, the end 31 of the cam engages the trunnion edge portion 32 adjacent its extremity 33. The notch 30, it will now be noted, serves to positively rotate the cam about its axis until the common contact point of the cam end and trunnion edge is above the plane determined by the cam axis and door-bearing axis, after which the point 50 31 of the cam moves out of the notch and along the trunnion edge 32 as described. To insure a resilient pressure tending to maintain the door closed at all times, the spring 55 16 is preferably so shaped that slight torsional distortion thereof will exist when the door is in closed position. In this manner, a constant resilient force is provided which tends to maintain the door in closed position at all times, it being obvious that the effective moment of such force, when the door is fully extended, is preferably slightly less than the weight moment of the door.

Preferably formed on the plate 19 at its 60 front edge is a transversely extending flange

36 which is arranged to seat against the rear of the door frame 8 and extends outwardly from the plate at least as far as the outer cam face 37. By referring to Figure 2 it will now be seen that when the door is fully extended, the side 38 of the notch 30 will engage the inner face of the flange 36 to thereby prevent the further downward movement of the door, thus providing a stop which will not cause an undue strain on the door frame.

In the embodiment shown in Figure 4, the operative relation between the spring 41 and trunnion 42 is provided by tangentially extending the outer end 43 of the spring 40 to operate in a groove 44 provided in the rearward edge of the trunnion. Since in this form of the invention, the spring coils may then be mounted on a fixed stud 45 extending from the plate, a greatly simplified structure results.

It will now be particularly noted that a counterbalancing means has been shown which permits the ready insertion or removal of the door trunnions in their perforations without necessitating the removal of any part of the counterbalancing mechanism. It will be further noted that either one or both supporting trunnions of a door may be provided with the counterbalancing means of our invention, or that one or more trunnions independent of the door supporting and pivoting means may be provided to have the counterbalancing device associated therewith.

We claim:

1. In an oven, a frame including a door frame, a door pivotally mounted at the lower edge of the opening in said door frame, a cam shaft mounted for rotation about an axis parallel to and rearwardly of the bearing axis of said door, a bracket fixed to said frame and provided with a bearing for said shaft, a coil spring mounted on said shaft and having an end fixed thereto, means on said bracket for preventing a circumferential movement of the other end of said spring; a cam lever fixed to said shaft, a stop provided on said frame, and a trunnion extending from said door having a portion thereof arranged to actuate said cam lever during pivotal movement of the door, a portion of said cam operating trunnion portion being arranged to operatively engage said stop when said door is in fully opened position, and said trunnion having a depressed portion in which said cam is arranged to seat when the door is in closed position.

2. In an oven, a door frame, a door pivotally mounted at the lower edge of the opening in said door frame, a cam lever mounted for rotation about an axis parallel to and rearwardly of the bearing axis of said door, a trunnion extending from said

door and having a portion thereof arranged to engage against and actuate said cam lever upon an opening movement of said door, and means associated with said cam lever operative to resiliently maintain said cam lever and trunnion in engaged relation, said trunnion having a depressed portion in

which said cam is arranged to seat when the door is in closed position.

In testimony whereof, we have hereunto set our hands at Oakland, California, this 15th day of November, 1924.

FREDERICK A. GERCICH.
JOSEPH B. GARDNER.
